VARIABLE RESISTANCE CONTROL

John D. Van Benthuysen and Wilbert H. Budd, Elkhart, Ind., assignors to CTS Corporation, Elkhart, Ind., a corporation of Indiana

Filed Feb. 24, 1965, Ser. No. 434,891

7 Claims. (Cl. 338—180)

ABSTRACT OF THE DISCLOSURE

A rectilinear variable resistance control in a housing employing a lead screw drivably engaging a contact assembly having a contact wipably engaging a resistance element. A clutch assembly having a first cylindrical member integral with the lead screw, a second cylindrical member connected to a rotatable member extending outwardly of the housing and a resilient member biasing the cylindrical members into engagement prevents damage to the control.

The present invention relates to variable resistance controls, and, more particularly, to a rectilinear variable resistance control.

Rectilinear variable resistance controls have been advantageously employed wherever a compact control is necessary with a fine degree of adjustment. The operating member of such controls, i.e., a contact assembly, is generally enclosed in a housing, and it is difficult to determine when the contact assembly has reached the end of its travel in either direction. Clutches for limiting the travel of the contact assembly in variable resistance controls are available on the market but are inadequate for use in controls having a minimum housing length. It would, therefore, be desirable to provide a rectilinear variable resistance control with an improved clutch assembly of a short axial distance for preventing damage to the control when an operator continues to adjust the control after the contact assembly has reached the end of its travel in either direction.

In the manufacture of rectilinear variable resistance controls, it is necessary that chucking action between the contact arm of a contactor and the lead screw be kept to a minimum. Various constructions on the market have received a certain degree of acceptance, however, a certain amount of free play exists and becomes apparent when the rotation of the lead screw is reversed. It would, therefore, be desirable to provide a variable resistance control having the contactor fixedly secured to the drive block.

One of the factors determining the wattage rating of a variable resistance control is the ability of the resistance element to dissipate heat rapidly. Generally this is no problem since the size of the resistance element can be increased to accommodate the necessary wattage rating. However, when the size of the resistance element is limited, it is necessary that other means be employed for dissipating the heat of the resistance element. It would, therefore, also be desirable to provide a rectilinear variable resistance control employing a resistance element having means for dissipating heat rapidly.

Many variable resistance controls are exposed to atmospheric conditions injurious to the operable members of the control. In an effort to seal such controls and still

2

maintain flush walls for stacking the controls a cover closing the housing is provided with a peripheral groove extending along the junction between the housing and the cover, and bonding material is disposed in the groove for securing the cover to the housing.

Accordingly, it is an object of the present invention to provide an improved variable resistance control.

An additional object of the present invention is to provide a variable resistance control having a clutch assembly electrically insulating a lead screw from a rotatable member.

A further object of the present invention is to provide a variable resistance control having a contactor welded to a drive block of electrically conductable material threadedly engaging a rotatable lead screw.

Still an additional object of the present invention is to provide a groove extending at least partially along a junction formed by a housing and a cover of a variable resistance housing with bonding material disposed in the groove for sealing the cover to the housing.

Still another object of the present invention is to provide a variable resistance control having a wirewound resistance element having a mandrel of high thermal conductivity.

25 A still further object of the present invention is to provide a rectilinear variable resistance control with a clutch assembly having a pair of cylindrical members having a high diameter to thickness ratio.

Further objects and advantages of the present invention will become apparent as the following description proceeds, and the features of novelty characterizing the invention will be pointed out with particularity in the claims annexed to and forming a part of this specification.

Briefly, the present invention is concerned with a variable resistance control having a housing provided with a cavity opening to one side thereof receiving a resistance element, a lead screw, a contact assembly for wiping contact with the resistance element and a clutch assembly for disengaging the lead screw from a rotatable member 40 when the contact assembly reaches the end of its travel in either direction in the housing. The clutch assembly comprises a first cylindrical member integral with the lead screw, a second cylindrical member connected to the rotatable member and a resilient member biasing the cylindrical members into engagement. In one embodiment of the invention, the contact assembly comprises a drive block of electrically conductable material threadedly engaging the lead screw and having a contactor welded to the drive block. Insulating means such as an electrically 45 insulatable second cylindrical member is employed between the lead screw and the rotatable member. A cover closes the cavity or open side of the housing and a peripheral groove extending at least partially around the junction between the housing and the cover is filled with a bonding material securing the cover to the housing thereby 50 providing flush outer sides for the housing. Tubular members projecting from the housing are received in apertures provided in the cover.

60 For a better understanding of the present invention, reference may be had to the accompanying drawings wherein the same reference numerals have been applied to like parts and wherein:

FIGURE 1 is an isometric view of the variable resistance control made in accord with the present invention;

FIGURE 2 is an end view of the control shown in FIGURE 1;

FIGURE 3 is a side elevational view of the control of FIGURE 1 with the cover removed;

FIGURE 4 is a sectional view taken along line IV—IV of FIGURE 3, assuming that FIGURE 3 is shown in full;

FIGURE 5 is an end view of the control similar to FIGURE 2 except that the cover is not fixedly secured to the housing;

FIGURE 6 is an exploded view of the control of FIGURE 1;

FIGURE 7 is an isometric view of the contactor shown in FIGURES 3 and 6 of the drawings; and

FIGURE 8 is a fragmentary section of another embodiment of a clutch assembly employed in the present invention.

Referring now to the drawings, there is illustrated a variable resistance control, generally indicated at 10, comprising a housing 11 having a bottom wall 11a, side walls 11b and 11c, a top wall 11d and end walls 11e and 11f defining a hollow interior or cavity 12. The housing 11 is provided with a pair of transverse openings 13 to facilitate mounting of the control 10. The openings 13 are partially defined by a pair of tubular members 14 (see FIGURE 6) projecting outwardly of the housing adjacent to the cavity 12. A cover 15 provided with a pair of transverse apertures 16 closes the cavity 12 of the housing 11, and the tubular members 14 positioned in the apertures 16 of the cover 15 align the cover with the housing. The outer surface of the cover 15 defines one of the side walls 11b of the housing. The cover 15 and the housing 11 are preferably molded from a suitable molding resin such as phenol condensation composition or a methacrylate resin. For the purpose of maintaining flush exterior walls for the housing to facilitate stacking thereof, a peripheral groove 17 extends at least partially around the junction 18 between the housing 11 and the cover 15 as best shown in FIGURES 4 and 5 of the drawings. A suitable epoxy bonding material 19 is deposited in the groove and, upon solidification of the bonding material, the cover is fixedly secured to the housing without having any bonding material above the surface of the walls of the housing. The groove 17 also provides a suitable space for the bonding material 19 after the cover is assembled to the housing thereby eliminating any harm which could result if the bonding material 19 were applied to the edges of the housing and the cover before assembly and some of the bonding material 19 contacted one of the operating members in the housing.

Preferably and as best shown in FIGURE 3 of the drawings, a means defining a resistance path 20 is mounted in the lower portion of the cavity 12 intermediate the transverse openings 13. The means defining the resistance path 20 can be a wirewound element, a carbon element or a glass frit resistance element deposited on an electrically nonconductable substrate such as steatite. In the embodiment shown in the drawings, the resistance element is a wirewound element preferably comprising a solid electrically conductable mandrel 21 of suitable material, such as copper, and a layer of insulation coats the outer surface of the mandrel for insulating a coiled helical resistance wire 22 wound thereon. One end 22a of the resistance wire 22 is connected to the solid electrically conductable mandrel 21 and the other end 22b of the resistance wire is connected to a suitable terminal lead 23. Another terminal lead 24 is connected to the mandrel 21 thereby including the mandrel as a conductive portion of a circuit and also eliminating the need for a longer terminal lead to the other end 22a of the resistance eslement 22. Since a metal such as copper is a good thermally conductive material, the heat generated by the resistance element is rapidly absorbed and dissipated by the mandrel 21.

In order to wipe a contactor 25 intermediate the ends

of the resistance path 20, a lead screw 26 is rotatably mounted in the housing. The housing 11 is provided with a pair of arcuate bearing surfaces 27 and 28 rotatably supporting the ends of the lead screw 26. The end 26a of the lead screw 26 is supported by the bearing surface 27 and has a diameter substantially the same as the threaded portion of the lead screw. The other end of the lead screw 26 is defined by a cylindrical membre 29 supported by the bearing surface 28, the diameter of the cylindrical member 29 being substantially larger than the threaded portion of the lead screw. A contact assembly 10 operably connected to the lead screw 26 comprises an electrically conductable drive block 30 threadedly engaging the lead screw 26. The contactor 25 is preferably 15 fixedly secured to the drive block 30 by spot welding thereby eliminating any free play therebetween. A C-washer 26b disposed in the slot 26c adjacent to the end 26a limits travel of the drive block 30 on the lead screw in one direction. For the purpose of electrically 20 connecting the contactor to an electrical circuit, a collector 31, is suitably mounted in the cavity of the housing. The collector 31 is of U-shaped construction, the bight portion of the U being in contact with the contactor 25, the legs of the U being disposed in suitable 25 slots forming part of the cavity 12 of the housing 11. A terminal lead 31a is connected to one of the legs of the collector 31. The contactor 25 is provided with a contact arm 25a for wiping contact with the resistance path 20 and a collector arm 25b for wiping contact with 30 the collector 31.

Preferably and in accord with the present invention, a clutch assembly 32 interposed between the externally 35 rotatably means defined by a slotted shaft 33 and the lead screw 26 prevents damage to the housing or to the threaded portion of the lead screw and the internal thread of the drive block 30 when the contact assembly, i.e., the drive block 30 and the contactor 25, reaches the end of its travel in either direction along the resistance path. The clutch assembly 32 comprises a pair of 40 cylindrical members 29 and 34 of the same diameter, the first cylindrical member 29 also functioning as the bearing for one end of the lead screw. The second cylindrical member 34 integral with the rotatable means 33 is rotatably supported by the bearing surface 28 thereby 45 remaining in proper alignment with the first cylindrical member. It is critical that the ratio of the diameter of each of the cylindrical members 29 and 34 to the diameter of the lead screw be substantially greater than 1:1. In a control made in accord with the present invention, the diameter of the cylindrical members was .124 inch and the diameter of the lead screw was .058 inch resulting in a ratio of 2.2:1. Each of the cylindrical members 29 and 34 is provided with a clutch face 29a and 34a respectively, and a resilient means, e.g., a tension sealing washer 36, circumposing the rotatable means 33 biases the clutch faces into engagement thereby connecting the rotatable means 33 to the lead screw 26. For the purpose of maintaining a positive drive between the rotatable means 33 and the lead screw 26 when the rotatable means drives the lead screw and the contactor 50 25 is intermediate the ends of the resistance path 20, the clutch face 29a of the first cylindrical member 29 is provided with a groove 29b and the clutch face 35a of the second cylindrical member 34 is provided with an elongated bead 34b disposed in the groove 29a. Thus any torque applied to the rotatable means 33 is transferred to the lead screw 26 and, when the drive block 30 reaches the end of its travel in either direction, the lead screw encounters substantial resistance to rotation 55 60 65 70 causing the clutch faces 29a and 34a to rotate relative to each other, thereby preventing damage to any portion of the control 10.

It will be appreciated that when the drive block 30 is of an electrically conductable material the current is transmitted from the contactor 25 to the lead screw 26.

It is, therefore, necessary that some means be employed for electrically insulating the rotatable means 33 from an electrically conducting lead screw 26. To this end, the rotatable means 33 is, preferably, of an electrically non-conductive material. It is to be understood, however, that if the rotatable means is of similar electrically conductive material such as the lead screw, an electrically insulatable clutch disc 37 is interposed between the clutch faces as shown in FIGURE 8 of the drawings. The external portion of the rotatable means 33 can be slotted for receiving a suitable tool, such as a screwdriver. As best seen in FIGURE 4 of the drawing, an inwardly extending projection 15a integral with the cover engages and maintains the one end 26a of the lead screw 26 against the bearing surface.

In order to secure the terminal leads 23, 24 and 31a extending outwardly of the housing 11, the housing is provided with a slot 38 and a pair of posts 39 extend outwardly from one of the walls of the slot providing three passageways, the terminal leads 23, 24 and 31a being disposed in the passageways. An inwardly turned member 15b integral with the cover 15 and disposed in the slot 38 secures the terminal leads in the housing.

While there has been illustrated and described what is at present considered to be a preferred embodiment of the present invention, and a single modification thereof, it will be appreciated that numerous changes and modifications are likely to occur to those skilled in the art, and it is intended in the appended claims to cover all those changes and modifications which fall within the true spirit and scope of the present invention.

What is claimed as new and desired to be secured by Letters Patent of the United States is:

1. In a variable resistance control having a housing, a resistance element disposed in the housing, a lead screw rotatably journaled in the housing, a contactor for making wiping contact with the resistance element, and means connecting the contactor to the lead screw for moving the contactor intermediate the ends of the resistance element as the lead screw is rotated the improvement comprising a pair of engaging members having clutch faces, one of the engaging members being drivingly connected to the lead screw, the other of the engaging members being rotatable externally of the housing, and electrically nonconducting resilient means biasing one of the engaging members into driving engagement with the other engaging member.

2. In a variable resistance control having a housing, a resistance element disposed in the housing, a lead screw rotatably journaled in the housing, a contactor for making wiping contact with the resistance element, and means drivingly connecting the contactor to the lead screw for shifting the contactor intermediate the ends of the resistance element as the lead screw is rotated the improvement comprising a first means defining a clutch face integral with the lead screw and normal to the axis thereof, a rotatable means extending outwardly of the housing, a second means defining a clutch face drivingly connected to the rotatable means, a projection carried by one of the clutch faces, the other clutch face being provided with a recess receiving the projection, and electrically nonconductive resilient means biasing one of the clutch faces into driving engagement with the other clutch face.

3. In a variable resistance control the combination of a housing, means defining a resistance path disposed in the housing, a lead screw rotatably journaled in the housing, contact means engaging the resistance path, the contact means being drivingly connected to the lead screw for shifting the contact means intermediate the ends of the resistance path, a shaft extending outwardly of the housing, clutch means drivingly connecting the shaft to the lead screw, and electrically nonconducting resilient means sealing the inside of the housing around the shaft, said resilient means also biasing the shaft against the lead screw thereby enabling the shaft and lead screw to rotate as a

unit until the contact means reaches one of the ends of the resistance path.

4. In a variable resistance control the combination of an elongated housing provided with a cavity, means defining a resistance path disposed in the cavity of the housing, a lead screw rotatably journaled in the housing in spaced parallel relationship to the means defining the resistance path, a contact assembly driven by the lead screw for making wiping contact with the resistance path intermediate the ends thereof, rotatable means extending outwardly of the housing, a first cylindrical member provided with a clutch face and integral with the lead screw, a second cylindrical member provided with a clutch face and integral with the rotatable means, the clutch faces being normal to the axis of the lead screw, one of the clutch faces being provided with an elongated groove, the other clutch face being provided with an elongated bead disposed in the elongated groove, and resilient means comprising an O-ring circumposing the rotatable means, said resilient means biasing the clutch faces together for connecting the rotatable means to the lead screw whereby upon rotating the contact assembly to one of the ends of the resistance path relative rotation between the clutch faces will occur.

5. A variable resistance control comprising a housing of electrically nonconductive material, a resistance element disposed in the housing, a pair of terminal leads connected to the ends of the resistance element, a lead screw rotatably mounted in the housing in spaced relationship to the resistance element, an electrically conductable internally threaded drive block threadedly engaging the lead screw, a collector, a contractor secured to the drive block for making wiping contact with the resistance element and the collector intermediate the ends thereof, a rotatable means projecting outwardly of the housing, means insulating the rotatable means from the lead screw, a first cylindrical member integral with the lead screw, a second cylindrical member connected to the rotatable means, one of the cylindrical members being provided with a groove, the other cylindrical member being provided with a projection disposed in the groove, and an O-ring biasing the cylindrical members into engagement with each other whereby upon rotation of the rotatable means the lead screw rotates with the rotatable means until the contractor reaches one of the ends of the resistance element.

6. A variable resistance control comprising a housing having a cavity, means defining a resistance path disposed in the cavity of the housing, a lead screw rotatably journaled in the housing in spaced parallel relationship to the resistance path, a contact assembly operably connected to the lead screw for making wiping contact with the resistance path, a pair of tubular members projecting laterally of the housing, a cover provided with a pair of spaced apertures closing the cavity of the housing, the tubular members being received in the apertures of the cover, the housing being provided with an end portion, the end portion of the housing being provided with a slot, a plurality of terminal leads connected to the means defining the resistance path and to the contact assembly and disposed in the slot, and an inwardly turned end portion integral with the cover engaging the terminal leads and fixedly securing the terminal leads in the slot.

7. In a variable resistance control the combination of a housing provided with a cavity, a resistance element disposed in the cavity of the housing, a lead screw rotatably journaled in the housing, a contact assembly for making wiping contact with the resistance element and drivingly connected to the lead screw, a first cylindrical member integral with the lead screw having a clutch face normal to the axis of the lead screw, the housing being provided with a bearing surface supporting the cylindrical member, rotatable means extending outwardly of the housing, a second cylindrical member integral with the rotatable means and having a clutch face normal to the axis of rota-

tion of said rotatable means, the second cylindrical member being supported by the bearing surface, a clutch disc interposed between the cylindrical members, and a resilient means biasing one of the cylindrical members toward the other cylindrical member for drivingly connecting the 5 rotatable means to the lead screw through the clutch disc.
